US0D1008946S

(12) **United States Design Patent** (10) **Patent No.:** **US D1,008,946 S**
(45) **Date of Patent:** **** Dec. 26, 2023**

(54) **ELECTRIC SCOOTER**

(71) Applicant: **ZHEJIANG TAOTAO VEHICLES CO., LTD.**, Lishui (CN)

(72) Inventors: **Jianbing Wu**, Lishui (CN); **Haibo Zhu**, Lishui (CN); **Matao Cao**, Lishui (CN)

(73) Assignee: **ZHEJIANG TAOTAO VEHICLES CO., LTD.**, Lishui (CN)

(**) Term: **15 Years**

(21) Appl. No.: **29/864,478**

(22) Filed: **May 31, 2022**

Related U.S. Application Data

(62) Division of application No. 29/652,091, filed on May 8, 2020, now Pat. No. Des. 972,652.

(57) **CLAIM**

The ornamental design for an electric scooter, as shown and described.

DESCRIPTION

FIG. 1 is a perspective view of an electric scooter showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken line showing of the electric scooter is for the purpose of illustrating portions thereof and forms no part of the claimed design.

The "Elmoto" lettering forming part of the disclosure is a registered trademark of Celerity Motor GmbH.
